COMBINATION TOWEL STORAGE, DISPENS-
ING, AND DISPOSAL CABINET

George M. Stewart, Kansas City, Kans.

Application September 12, 1949, Serial No. 4,968

Term of patent 7 years

(Cl. D4—3)

To all whom it may concern:

Be it known that I, George M. Stewart, a citizen of the United States, residing at 4325 Cambridge, in the county of Wyandotte and State of Kansas, city of Kansas City, have invented a new, original, and ornamental Design for a Combination Towel Storage, Dispensing, and Disposal Cabinet, of which the following is a specification, reference being had to the accompanying drawing, forming a part thereof.

Fig. 1 is a perspective view of combination towel storage, dispensing, and disposal cabinet, showing my new design, taken at one angle with respect thereto showing the doors thereof closed; and,

Fig. 2 is a perspective view thereof taken from another angle with the doors open.

The back is without ornamentation.

I claim:

The ornamental design for a combination towel storage, dispensing, and disposal cabinet, as shown, and described.

GEORGE M. STEWART.
